CONNECTOR FOR STRANDED CABLE

Arthur A. Berndt, Chicago, Ill., assignor to Electroline Company, Chicago, Ill., a corporation of Illinois

Application April 4, 1952, Serial No. 280,512

5 Claims. (Cl. 174—94)

1

The invention relates to improvements in connectors for stranded cable and has reference more particularly to an improved cable connector having separate sets of gripping members for individually gripping the center wire and the outer strands of the cable.

Electrical conductors used for aerial power lines normally consist of copper or aluminum. As aluminum has a low tensile strength it is necessary to combine the aluminum wires with one or more steel wires in the form of a stranded cable. In order to successfully grip such a cable for anchoring the same to a support, the two metals must be individually clamped so that the strain will be divided between the two metals in proportion to their tensile strength and so that a contact of high conductivity will be made with the outer aluminum strands.

Accordingly an object of the invention is to assemble within a single conducting metal shell, two or more sets of separate gripping members designed to grip and hold metal wires of different strength, conductivity and hardness, and wherein the intensity of the grip is controlled by varying the angle between the gripping member and its cage or shell.

Another object of the invention resides in the provision of a connector having gripping members for engaging the outer wires of the cable and having gripping wedges for securely gripping and holding the center wire of the cable, and wherein the gripping elements operate independently of each other and stress applied to either set of gripping elements is not transmitted to the other set.

A further object is to provide a connector for stranded cable having one or more sets of independent gripping elements and which are capable of adjustment to any variance in the size of either the steel center strand or in the outer aluminum wires as may occur due to manufacturing tolerances or differences in type of construction for the same size cable.

A further object is to provide a stranded cable connector of improved construction and operation which will essentially consist of a metal shell having tapered end portions each housing a set of gripping members for holding the outer strands of the cable, and wherein said shell will also house a steel cage in tandem relation with respect to the gripping members respectively, which is secured to the shell by peening and contains a set of gripping wedges whereby to grip the center steel wire of the cable.

With these and various other objects in view

2

the invention may consist of certain novel features of construction and operation as will be more fully described and particularly pointed out in the specification, drawings and claims appended hereto.

In the drawings which illustrate embodiments of the invention and wherein like reference characters are used to designate like parts—

10 Figure 1 is an elevational view of the stranded wire connector of the invention with parts of the shell being broken away to show structural details of the gripping elements;

15 Figure 2 is an enlarged sectional view of one end of the present connector taken longitudinally and illustrating the construction of the gripper elements and their independent coaction;

20 Figure 3 is an enlarged sectional view of one end of the present connector similar to Figure 2, but illustrating the action of the gripping elements when in gripping relation with a stranded wire cable;

Figure 4 is a transverse sectional view taken on line 4—4 of Figure 3;

25 Figure 5 is a transverse sectional view taken on line 5—5 of Figure 3;

Figure 6 is a transverse sectional view taken on line 6—6 of Figure 3;

Figure 7 is a transverse sectional view taken on line 7—7 of Figure 3;

30 Figure 8 is a detail sectional view illustrating the coupling means for the gripping members; and,

Figure 9 is a perspective view of the retaining cone for the gripping wedges.

35 The invention is shown as embodied in a connector for stranded wire or cable, having outer wires of aluminum or similar material of high electrical conductivity, and having a steel center wire which assumes the major part of the tension placed on the conductor when in use.

As best shown in Figure 1, the connector includes a housing or casing of tubular form, generally designated by the numeral 12, and which may be of any suitable metal, preferably copper or aluminum and having at least one end thereof tapered to form the tapering end portion 13. In the illustrated embodiment of Figure 1, both ends are reduced in diameter by a swaging operation, and accordingly, one end is identified by the numeral 13 and the other end by the numeral 14. It will be observed that the metal at each end opening, namely 15 and 16, is correspondingly increased in thickness. This is a desirable feature since the added metal imparts additional strength to the end portions, whereby they effec-

tively withstand the tensile strains applied thereto. Each of the end openings 15 and 16 of course is larger in diameter than the stranded cable adapted to be inserted through the opening and into gripping relation with the gripping elements located within the casing.

In accordance with the invention, a set of gripping members is provided for engaging and holding the outer wires of the cable, and a pair of gripping wedges is provided for gripping and holding the center steel wire of the cable. Figure 3 illustrates the operative position of the independent sets of gripping elements for the stranded wire cable. The gripping members 17 are associated in a set of three or four members, 15 and located at each tapered end portion of the casing in contact with the tapering walls of said portion. Each set of gripping members may be described as cone-shaped, and each set is held together as a unit by the resilient member 18 of circular form, having location in the grooves 20 formed transversely of the members. A central bore or passage extends longitudinally of each set of gripping members, the same being indicated by numeral 21, and being formed by circular grooves in the individual members. The surface of the bore is serrated to form teeth for biting into the outer wires of the conductor, as a result of which the conductor is held to the gripping members.

In accordance with the invention, means are provided for retaining the gripping members in operative connected relation so that they move and coact as a unit. The structure is best shown in Figures 6 and 8, and essentially consists of a metal ring 22, having a plurality of pins 23 spaced around the ring and extending radially thereof. Each gripping member 17 is provided with a rear extension 24, the said extension projecting approximately horizontally and rearwardly of its gripping member and having a length substantially equal to the width of the ring 22. Also it will be noted that the extensions have telescoping relation with the ring. Each extension is provided with a central opening of a diameter larger enough to receive one of the pins 23, which extend radially from the ring 22. As a result, the gripping members 17 are articulately connected to the ring and thus the members are joined to each other so that in combination with the resilient member 18, they move and coact as a unit in the gripping of the conductor.

The structure for accommodating the gripping wedges 26 essentially consists of a metal cage 27, which may be of steel or other suitable material, and which is inserted within the casing 12 of the connector before its respective end portion is swaged into tapered form. A cage is accordingly inserted in each end of the casing, with the beveled opening 28 being located toward its respective set of gripping members. Since the cage is provided with tapering interior surfaces 30, the said rear end of the cage is directed toward the center of the connector, or in other words, the pair of cages inserted within a connector have their rear ends 31 directed toward each other. Each cage 27 is secured to the casing 12 by a peening operation, which indents the metal of the casing as at 32, the same extending completely around the casing. The cage when in secured relation within the casing is located rearwardly of and in spaced relation with respect to its set of gripping members. The space between the parts is occupied by the coil spring 33, which

bears at its left-hand end against the front wall of the cage 27 and seats at its other end in the cup member 34. The cup member in turn seats on the ring 22 and the extensions 24 so that the action of the coil spring 33 is to urge the gripping members in a forward direction to maintain them in contact with their tapering surfaces.

The gripping wedges 26 are adapted to contact the interior tapering surfaces 30 of the cage 27, and in order to control the action of the gripping wedges, they are held by a retainer, generally designated by the numeral 35. The retainer is best shown in Figure 9, and it will be observed that the same is approximately cone-shaped, having the tapered nose 36 and the rear hub portion 37. The body of the retainer between the ends and the hub portion is slotted diametrically to provide a pair of longitudinal slots, indicated by the numeral 38, and in which the pair of gripping wedges 26 are located. The outer surface of each gripping wedge conforms to the interior taper 30 of the cage, and it will be seen that each wedge is provided with a semi-circular recess on its inner surface which in combination forms the central bore or passage 40. In order to assist the gripping wedges to grip and hold the center wire of the conductor, serrations or teeth are formed in the recesses. The coil spring 41 functions to urge the retainer 35 in a forward direction, whereby to maintain the gripping wedges 26 in contact with the tapering walls 30. Said spring 41 seats at its left-hand end in the cup member 42 located at the rear end of the cage 27 and being held within the rear open end of said cage by a peening or hammering operation on the rear end wall of the cage, which peens over the inner edge of said wall as at 43. The right-hand end of the coil spring 41 encircles the hub portion 37 and seats against the body portion of the retainer 35.

When a conductor, such as the stranded cable 45, is inserted in the open end 16 of the casing, it will be seen that the center steel strand 46 of the cable will pass through the central bore 21 of the gripping members, through the central opening 47 in a cup member 34, to eventually enter the central opening indicated by the numeral 28 in the cage 27. Upon this taking place, the stranded portion of the cable will have engaged the set of gripping members 17 at this end of the connector. The gripping members are flared as at 48 in order to accommodate the stranded wire portion of the conductor, and continued movement of the conductor within the casing will cause the set of gripping members 17 to move rearwardly against the tension of coil spring 33. As the gripping members move rearwardly, they expand, and in doing so they accommodate the stranded portion of the conductor, permitting inward movement of the same until contact is made with the cup member 34. Movement of the gripping members in a rearward direction takes place as a unit since the members are connected to each other through the pins 23 and the ring 22. Likewise, movement of the gripping members in a forward direction takes place as a unit, and they coact to grip the stranded wire portion of the cable, preventing release of the cable from the connector.

The gripping wedges have action substantially simultaneously with that of the gripping members, as the center steel strand 46, upon entering the cage 27, is likewise caused to enter the retainer 35, and engagement with the gripping wedges necessarily results. At first the retainer 35 and

the wedges 26 will move rearwardly against the tension of the coil spring 41. Eventually, however, the gripping wedges will expand and assume full contact with the center steel strand, and upon forward tension being placed on the cable, the wedges will engage the tapering surfaces 30, causing the wedges to bite into and grip the center steel strand.

In accordance with the invention, the intensity of the grip effected by the gripping members and by the gripping wedges respectively, can be adjusted by varying the taper of the surfaces with which the elements contact. The particular angle of the taper for the gripping members, and likewise the particular angle of the taper for the gripping wedges, will vary according to the strength, hardness, conductivity, elasticity and ductility of the various metals in the cable in order to produce a successful gripping device. The sets of gripping elements are separate, and they operate independently of each other. Any strain applied to either side is not transmitted to the other. For example, greater gripping and holding effort may be expended by the gripping wedges and their associated structure on the center steel strand of the cable than is expended by the gripping members, and should this be the case, the same is not transmitted in any sense to the gripping members, which may be effective with somewhat less intensity on the outer wires of the stranded cable. The use of independent gripping elements also provides for their automatic adjustment due to variance in the size of either the steel or aluminum strand, as occurs due to manufacturing tolerances, or difference in type of construction for the same size of cable.

The invention is not to be limited to or by details of construction of the particular embodiment selected for illustration in the drawings, as various forms of the device will of course be apparent to those skilled in the art without departing from the spirit of the invention or the scope of the claims.

What is claimed is:

1. A connector for stranded wire conductors comprising a tubular casing having a tapering end portion, gripping members arranged within said tapering end portion and adapted to receive and grip the outer wires of a conductor inserted within the tapering end portion, means yieldingly retaining the gripping members in operative connected relation so that they coat as a unit in gripping the conductor, other gripping elements located rearwardly in tandem relation with respect to the gripping members and operative to grip and hold the center wire of said conductor, said other gripping elements including a cylindrical cage located within the casing and secured thereto, said cage having tapering surfaces interiorly thereof, a plurality of gripping wedges located within the cage in contact with the interior tapering surfaces thereof, a retainer for the gripping wedges, and resilient means for the gripping members and wedges respectively, for urging the parts in a forward direction to maintain them in contact with their tapering surfaces.

2. In a connector for stranded cable having outer wires of aluminum and a center steel wire, the combination including a tubular casing having a tapering end portion, a set of gripping members within said tapering end portion and adapted to receive and grip the outer wires of a stranded cable inserted within the tapering end portion, a ring member at the rear of said gripping members

for retaining the members in operative connected relation so that they coat as a unit in gripping the cable, a cylindrical cage having tapering interior surfaces located rearwardly in spaced relation to the gripping members and being fixedly secured to the casing, a set of gripping wedges within the cylindrical cage in contact with the tapering interior surfaces thereof and adapted to grip and hold the center wire of said cable, a retainer for said gripping wedges, and resilient means for the gripping members and wedges respectively, for urging the parts in a forward direction to maintain them in contact with their tapering surfaces.

3. In a connector for stranded cable having outer wires of aluminum and a center steel wire, the combination including a tubular casing having a tapered end portion, a set of gripping members within said tapered end portion and adapted to receive and grip the outer wires of a stranded cable inserted within the tapering end portion, a ring member at the rear of said gripping members having articulated relation with each member for operatively connecting the members so that they coat as a unit in gripping the cable, a cylindrical cage having tapering interior surfaces located rearwardly in spaced relation to the gripping members and being fixedly secured to the casing, a set of gripping wedges within the cylindrical cage in contact with the tapering interior surfaces thereof and adapted to grip and hold the center wire of said cable, a retainer having slots for receiving the gripping wedges, and resilient means for the gripping members located between the members and the cage for urging the members in a forward direction to maintain them in contact with their tapered end portion.

4. A connector for stranded cable as defined by claim 3, additionally including other resilient means located within the cage in rear of the retainer and operative to yieldingly urge the retainer in a forward direction to maintain the gripping wedges in contact with their tapering surfaces.

5. In a connector for stranded cable and the like, the combination including a tubular casing having a tapered end portion, a set of gripping members within said tapered end portion and adapted to receive and grip the outer wires of a stranded cable inserted within the tapered end portion, said gripping members as a set being cone-shaped and having surfaces conforming to and in contact with the tapering walls of said portion, a rear extension provided by each gripping member, a ring member at the rear of said gripping members, said extensions having telescoping relation with the ring member, means projecting radially from the ring member and having articulated relation with the extensions respectively, so that they move and coat as a unit in gripping the cable, and a coil spring for the gripping members for urging the members in a forward direction to maintain them in contact with the walls of said tapered end portion.
